TWO-POSITION WORK HOLDING DEVICE

Alfred Houghton Esty, Santa Cruz, Calif., assignor of one-fourth to Walter H. Oellerich and one-fourth to Charles Grunsky, both of Santa Cruz, Calif.

Application May 4, 1942, Serial No. 441,605

5 Claims. (Cl. 29—39)

My invention relates to a two-position work-holding device, and more particularly to such a work-holding device which, in its smaller sizes, is ideally adapted for aid in model airplane construction.

Among the objects of my invention are: To provide a work-holding device having a plurality of guide members that can be moved from opposed, to parallel positions; to provide a work-holding device in which contours can be taken directly from drawing; to provide a work-holding device wherein opposed members can be symmetrically arranged on opposite sides of a center line; to provide a two-position work-holding device ideally adapted for model airplane construction or the like, and to provide a simple and efficient two-position work-holding device.

Other objects of my invention will be apparent or will be specifically pointed out in the description forming a part of this specification, but I do not limit myself to the embodiment of the invention herein described, as various forms may be adopted within the scope of the claims.

In the drawing:

Fig. 1 is a top plan view of one preferred form of my invention in a position with the guide members of each pair in parallel relationship.

Fig. 2 is a sectional view taken as indicated by the line 2—2 in Fig. 1.

Fig. 3 is a top plan view of the device of Fig. 1 rotated to place the guide members of each pair in opposed relationship.

Fig. 4 is the section taken as indicated by the line 4—4 in Fig. 3.

My invention may be more fully understood by direct reference to the drawing. A pair of end supports 1 and 2 are provided, each of these supports comprising right and left-hand portions 3 and 4 joined along one edge only by a centrally located hinge 5. Legs 6 and 7 are provided on each portion 3 and 4 respectively, these legs being provided with adjacent feet 10 and 11, preferably of rubber, as shown in Fig. 2 on the respective sides of the corners thereof. These feet are for contact with a foundation surface as the device is hinged as will be explained later.

The end faces of each of the end supports 1 and 2 are provided with hooks 12 and pins 14 to lock the right and left hand portions in the position shown in Fig. 1, the hinge thickness being compensated for by buttons 15 placed between the two portions of the end plate. In addition, the lateral edges of the end supports opposite from legs 6 and 7 are provided with hook and pin members 18 and 19 respectively to be used as will be

5 later described to lock the right and left hand portions when the device is rotated into the position shown in Fig. 3. The right and left hand portions of the two end supports 1 and 2 are respectively connected together by bars 20 and 21 which extends between them to position the end supports, when the latter are on a horizontal surface, in a vertical position. Bars 20 and 21 are provided with slots 22 extending between the end supports. In the slots are mounted a plurality of bolts 24 extending through the slots and through slotted extensions 25 of a plurality of guide members 26 positioned at right angles to the extensions. Surfaces 27 are preferably provided with centering lines 28 and 29. Each guide member may, therefore, be bolted to the bars by the use of wing nuts 31 mounted on the end of each bolt 24. The arrangement will permit the guide members to be moved to any position desired in a plane parallel to the plane of the bars.

There are a number of manners in which this two position work holder can be utilized. I prefer to describe it, for example, as being used for the construction of model airplanes. For such 20 model airplane construction the surfaces 27 of the guide members opposite to extensions 25 thereof, are preferably waxed. The guide members themselves are preferably made from soft pine or other suitable material. The device may be considered to be in position I when the end supports are locked as shown in Fig. 1, and in position II as shown in Fig. 3.

In illustrating one use of the device I may start with the device locked in position II as shown in Figs. 3 and 4. In this case the right and left hand portions 3 and 4 of the end supports 1 and 2 are swung outwardly on hinge 5 and the device locked together by engagement of hooks and pins 18 and 19. Under these conditions the device can either rest on a horizontal surface 30 on feet 11, or as I may prefer at the start, in a reverse position on the horizontal surface resting on buttons 15. If this is the case, due to the extent of legs 6 and 7, the ends of the guide members will be closer to the horizontal surface when resting on buttons 15 than they would be if resting on feet 11. Consequently, it is possible to place the device over a drawing which has, for example, only a center line and one side of a symmetrical figure drawn thereon, with buttons 15 contacting the drawing, and with center line 32 of the device directly over the center line of such drawing. Under these circumstances each guide member along one bar only, can be set to follow a line on the drawing. The device may

then be unlocked and rotated to position I, as shown in Fig. 1, and locked in that position by the use of locks 12 and pins 14. The other set of guide members may then be set to be parallel with the previously adjusted set, until the members of each side-by-side pair register properly. When both lines of guide members have been adjusted to register, structural members such as, for example, portions of an airplane fuselage may be pinned, clamped or otherwise temporarily applied to the guide member surface 27 to hold such structural portions in proper position with respect to the center lines 28 and 29 so that when the device is rotated into position II the structural members will come into proper relation one to the other. They may then be connected as, for example, by ribs, inserted between the structural members held on the separate sets of opposed guide members. In this manner two sides of a symmetrical structure may be joined. It will be noted that in position II of the device, structural portions held on the guide member surfaces 27 can be worked on either from top or bottom of the model under construction, simply by reversing the position of the work holder on the horizontal surface.

It will be understood, of course, that the above description of the operation of my device is simply illustrative of one purpose to which my clamp be applied, in constructing structures of symmetrical design. It should also be pointed out that other uses of the device will be apparent to those skilled in the art. For example, non-symmetrical structures (such as airplane wings) may be fabricated, as the alinement of guide members along one bar may be adjusted to one contour, and the opposite set of guide members may be adjusted to another, with structural portions of corresponding contour mounted on the guide members. Furthermore, while I have described my invention as being ideally adapted for use in the construction of model airplanes, in the larger sizes, it is obviously capable of handling structures of a size correlated with the size of the device.

While I have described my invention as having end plates hinged together in order that they may be rotated to place the guide members either in opposition or facing the same general direction, it is deemed an obvious equivalent to make the two portions of the device completely separable, and then to provide means, such as dowels, cooperating so that the two halves of the device may be taken apart and put together and locked in either of the two positions described. Furthermore, while I have described my device as having guide members which are adjustable on the bars, both as to angle and as to distance from the central plane, it is obvious that in case a large number of identical structures are to be fabricated all having the same contour, that guide members permanently fixed to the bars may be utilized. In addition my invention is deemed to include the use of a single half only with the guide members thereof holding a structural member in proper position for additional structural members to be attached thereto.

I claim:

1. A work-holding device comprising a pair of end plates, said end plates each being formed of a pair of sections; spaced connecting members joining corresponding sections of said end plates; a plurality of guide members disposed along each of said connecting members, with the guide members on one connecting member presenting ver-

tically disposed guide surfaces facing vertically disposed guide surfaces of guide members on said other connecting member; means enabling adjustment of the distances between corresponding guide members and the angular disposition of guide surfaces whereby said guide members may be adjusted to outline desired contours; means for securing said end plate sections to permit relative rotation of one with respect to the other through an angle sufficient to bring said guide surfaces into approximately a common plane for the temporary application of contour elements of a structure to be fabricated, following which said guide surfaces may be restored to their original opposing positions for the application of joining elements to said contour elements.

2. A work-holding device comprising a pair of end plates, said end plates each being formed of a pair of edge-to-edge disposed sections; spaced connecting members joining corresponding sections of said end plates; a plurality of guide members disposed along each of said connecting members, with the guide members on one connecting member presenting guide surfaces facing guide surfaces of guide members on said other connecting member; means enabling adjustment of the distances between opposing guide members and the angular disposition of guide surfaces whereby said guide members may be adjusted to outline desired contours; means for securing said end plate sections to permit relative rotation of one with respect to the other through an angle of approximately 180° to bring said sections into contact along different edges thereof, whereby said guide surfaces can be shifted into position for the temporary application of contour elements of a structure to be fabricated and then restored to their original positions for the application of joining elements to said contour elements.

3. A work-holding device comprising a pair of end plates, said end plates each being formed of a pair of edge-to-edge disposed sections; spaced connecting members joining corresponding sections of said end plates; a plurality of guide members disposed along each of said connecting members, with the guide members on one connecting member presenting guide surfaces facing guide surfaces of guide members on said other connecting member; means enabling adjustment of the distances between opposing guide members and the angular disposition of guide surfaces whereby said guide members may be adjusted to outline desired contours; means hingedly securing said end plate sections at adjacent corners thereof to permit relative rotation of one section with respect to the other through an angle of approximately 180° to bring said sections into contact along different edges thereof, whereby said guide surfaces can be shifted into position for the temporary application of contour elements of a structure to be fabricated and then restored to their original position for the application of joining elements to said contour elements.

4. A work-holding device comprising a pair of end plates, said end plates each being formed of a pair of edge-to-edge disposed sections; spaced connecting members joining corresponding sections of said end plates; a plurality of guide members disposed along each of said connecting members, with the guide members on one connecting member presenting guide surfaces facing guide surfaces of guide members on said other connecting member; means enabling adjustment of the distances between opposing guide members

and the angular disposition of guide surfaces whereby said guide members may be adjusted to outline desired contours; means for securing said end plate sections to permit relative rotation of one with respect to the other through an angle of approximately 180° to bring said sections into contact along different edges thereof, whereby said guide surfaces can be shifted into position for the temporary application of contour elements of a structure to be fabricated and then restored to their original positions for the application of joining elements to said contour elements, said guide surfaces having guide lines thereon to facilitate the application of such contour elements to said guide surfaces.

5. A work-holding device comprising a pair of end plates, said end plates each being formed of a pair of edge-to-edge disposed sections; spaced

10 connecting members joining corresponding sections of said end plates; a plurality of guide members disposed along each of said connecting members, with the guide members on one connecting member presenting guide surfaces facing guide surfaces of guide members on said other connecting member; means for securing said end plate sections to permit relative rotation of one with respect to the other through an angle of approximately 180° to bring said sections into contact along different edges thereof, whereby said guide surfaces can be shifted into position for the temporary application of contour elements of a structure to be fabricated and then restored to their original positions for the application of joining elements to said contour elements.

ALFRED HOUGHTON ESTY.
